ABSTRACT OF THE DISCLOSURE

There are disclosed stabilized coenzyme test compositions which comprise reduced nicotinamide-adenine-dinucleotide and/or reduced nicotinamide-adenine-dinucleotide-phosphate in admixture with at least one SH-group-containing organic compound, such as for example, cysteine, glutathione, thioglycollates, N-acetyl-homocysteine, etc. The compositions are porous powders, soluble in water. They need only be brought into solution and added to the material to be investigated for the analytical procedure to be carried out.

There are also disclosed the methods of making and using the compositions.

This application is a continuation-in-part of Ser. No. 689,005, filed Dec. 8, 1967, and now abandoned.

The present invention relates to stabilized coenzyme test compositions and to the preparation thereof.

More particularly, the invention relates to stabilized coenzyme test compositions containing di- and/or tri-phosphopyridine-nucleotide in reduced form, these two nucleotides also being known as reduced nicotinamide-adenine-dinucleotide and nicotinamide-adenine-dinucleotide-phosphate as well as to a process for making and using such compositions.

In carrying out enzyme investigations, particularly as required for diagnostic purposes, it is of the greatest importance that the materials necessary for the enzyme reactions are available in a form ready for use and in the correct proportions. For instance, it is highly desirable to have available a coenzyme composition which is stabilized against deterioration and thus remains suitable for use over prolonged periods of time.

However, heretofore providing such coenzyme test preparations has met with great difficulties. Thus, it has been found that coenzymes which are relatively stable in pure form, are frequently rendered unstable by the presence of other components, e.g., substrates, other coenzymes, buffers, and the like, of the test preparations so that, in the course of storage, they suffer from such a loss of activity that the known coenzyme test preparations are of doubtful practical utility. This applies particularly to combined preparations which contain reduced nicotinamide-adenine-dinucleotide and/or reduced nicotinamide-adenine-dinucleotide-phosphate.

In accordance with the invention it has surprisingly been found that SH-group-containing compounds have the ability to stabilize coenzyme test preparations.

Thus, according to the present invention, there are now provided stabilized, combined coenzyme test preparations

2

which comprise reduced nicotinamide-adenine-dinucleotide and/or reduced nicotinamide-adenine-dinucleotide-phosphate, together with at least one SH-group-containing compound as stabilizer.

5 The SH-group-containing compounds which are suitable for use according to the present invention are preferably organic compounds, for example, glutathione, cysteine, cysteine carbamide, acetyl-cysteine, homocysteine thiolactone, N-acetyl-homocysteine thiolactone, 10 thioglycollates or dithiothreitol, particularly in the case of combined coenzyme test compositions containing reduced nicotinamide-adenine-dinucleotide.

It is, of course, to be understood that the stabilizers must be so chosen that they do not interfere with or exert 15 any influence on the test reactions. This latter possibility can easily be ascertained by simple preliminary experiments and thereby avoided.

The SH-group-containing compounds which are particularly preferred are cysteine, cysteine carbamide and 20 acetyl-cysteine. An especial advantage of these substances is that they are considerably cheaper than, for example, glutathione.

The new test compositions according to the present invention can be prepared by the following method:

25 (a) Admixing in water of substances necessary for carrying out the reaction such as reduced nicotinamide-adenine-dinucleotide and/or reduced nicotinamide-adenine-dinucleotide-phosphate, possibly other coenzymes, as well as adjuvant substrates, buffer substances, other adjuvants and possibly also fillers together with the SH-group-containing stabilizer, in the amounts necessary for carrying out the specific reaction to provide an aqueous solution, the pH value and volume of which can then, if necessary or if desired, be adjusted in the known manner;

30 (b) Filling this solution in the desired amounts into suitable containers; and

(c) Lyophilizing the contents of the containers and thereafter immediately closing the same.

As fillers, there may be used those non-ionic organic 40 substances, such as gelatine, polyvinyl pyrrolidone, albumin and the like, which, as is known, simplify the lyophilization procedure.

The test compositions according to the present invention constitute porous powders which are readily soluble 45 in water and which, when stored in sealed containers, retain their activity over a period of several years. The compositions of the invention represent a considerable advance in the field of reagent compositions for carrying out coenzyme studies and analyses. In accordance with 50 the invention, it is now only necessary to dissolve the contents, comprising the instant compositions, of a sealed container, and such other materials, if any, needed for reaction, in a specified amount of water, add the material to be investigated, such as serum, and then to carry out 55 a defined analysis, as for example, a determination of extinction values in a photometer.

In addition to stabilizer, reduced nicotinamide-adenine-dinucleotide and/or reduced nicotinamide-adenine-dinucleotide-phosphate and the above-mentioned additional 60 materials, the stabilized preparations according to the present invention can also contain one or more additional coenzymes.

The following examples are given for the purpose of illustrating the present invention and are in no way to be construed as limiting the invention. In each instance,

stabilized coenzyme test compositions are provided, i.e., compositions containing coenzymes which are stable for a comparatively long period of time in a lyophilized condition.

EXAMPLE 1

Determination of lactate dehydrogenase (LDH)

	Grams
Na ₂ HPO ₄ ·2H ₂ O	2.43
NaH ₂ PO ₄ ·2H ₂ O	0.21
Sodium pyruvate	0.012
Glutathione	0.30
Serum albumin	0.30
NADH *	0.05

*NADH is reduced nicotinamide-adenine-dinucleotide.

were dissolved in 90 ml. bi-distilled water, and the pH value was adjusted to 7.6 with diluted solution of sodium hydroxide or hydrochloric acid. Then the solution was filled up to 100 ml. with bi-distilled water, frozen and freeze-dried.

EXAMPLE 2

Determination of the α -hydroxybutyrate dehydrogenase (α -HBDH)

	Grams
Na ₂ HPO ₄ ·2H ₂ O	2.43
NaH ₂ PO ₄ ·2H ₂ O	0.20
α -Ketobutyric acid	0.09
Glutathione	0.30
Serum albumin	0.30
NADH	0.05

The above substances in the amounts indicated were worked up in the manner specified in Example 1.

EXAMPLE 3

Determination of the sorbitol dehydrogenase (SDH)

	Grams
Triethanolamine hydrochloride	4.40
Sodium carbonate	0.50
Fructose	5.40
Glutathione	0.30
Serum albumin	0.30
NADH	0.05

The above substances in the amounts indicated were worked up in the manner specified in Example 1.

The stability of NADH with respect to temperature stress in the preparations in accordance with Examples 1, 2 and 3, above, compared to preparations without the stabilizing glutathione can be seen from Table I, below.

TABLE I.—STABILITY OF NADH WITH AND WITHOUT GLUTATHIONE (GSH) AT 33° C.

[Values given in mg. NADH after redissolution of the lyophilizate]

	With GSH	Without GSH
Preparation of Example 1:		
Initial value	50	50
1 week	48	41
3 weeks	47	25
8 weeks	45	5
Preparation of Example 2:		
Initial value	51	50
1 week	51	39
3 weeks	48	27
8 weeks	44	9
Preparation of Example 3:		
Initial value	52	48
1 week	50	40
3 weeks	50	33
8 weeks	45	15

It will be understood that the specification and examples are illustrative but not limitative of the present invention and that other embodiments within the spirit and scope of the invention will suggest themselves to those skilled in the art.

What is claimed is:

1. A stabilized coenzyme test composition consisting of at least one member selected from the group consisting of reduced nicotinamide-adenine-dinucleotide and reduced nicotinamide-adenine-dinucleotide phosphate and at least one SH-group containing compound as stabilizing agent wherein said SH-group containing compound is a member selected from the group consisting of cysteine, cysteine carbamide, acetyl-cysteine, glutathione, homocysteine thiolactone, N-acetyl-homocysteine thiolactone, and thioglycolate.
2. A composition as claimed in claim 1 wherein said SH-group containing compound is cysteine carbamide.
3. A composition as claimed in claim 1 wherein said SH-group containing compound is acetyl-cysteine.
4. A composition as claimed in claim 1 wherein said SH-group containing compound is homocysteine thiolactone.
5. A composition as claimed in claim 1 wherein said SH-group containing compound is N-acetyl homocysteine thiolactone.
6. A composition as claimed in claim 1 wherein said SH-group containing compound is thioglycolate.
7. A stabilized coenzyme composition consisting of at least one coenzyme selected from the group consisting of reduced nicotinamide-adenine-dinucleotide and nicotinamide-adenine-dinucleotide-phosphate and as a stabilizer for said coenzyme stabilizingly effective amounts of diethoxythritol.
8. A stabilized coenzyme composition consisting of at least one coenzyme selected from the group consisting of reduced nicotinamide-adenine-dinucleotide and nicotinamide-adenine-dinucleotide-phosphate and as a stabilizer for said coenzyme stabilizingly effective amounts of cysteine.
9. A stabilized coenzyme composition consisting of at least one coenzyme selected from the group consisting of reduced nicotinamide-adenine-dinucleotide and nicotinamide-adenine-dinucleotide-phosphate and as a stabilizer for said coenzyme stabilizingly effective amounts of glutathione.
10. A stabilized coenzyme test composition consisting of:

	Grams
Na ₂ HPO ₄ ·2H ₂ O	2.43
NaH ₂ PO ₄ ·2H ₂ O	0.21
Sodium pyruvate	0.012
Glutathione	0.30
Serum albumin	0.30
Reduced nicotinamide-adenine-dinucleotide	0.05
11. A stabilized coenzyme test composition consisting of:

	Grams
Na ₂ HPO ₄ ·2H ₂ O	2.43
NaH ₂ PO ₄ ·2H ₂ O	0.20
α -Ketobutyric acid	0.09
Glutathione	0.30
Serum albumin	0.30
Reduced nicotinamide-adenine-dinucleotide	0.05
12. A stabilized coenzyme test composition consisting of:

	Grams
Triethanolamine hydrochloride	4.40
Sodium carbonate	0.50
Fructose	5.40
Glutathione	0.30
Serum albumin	0.30
Reduced nicotinamide-adenine-dinucleotide	0.05
13. Process for stabilizing reduced nicotinamide-adenine-dinucleotide or reduced nicotinamide-adenine-dinucleotide-phosphate which consists of dissolving in

water at least one member selected from the group consisting of reduced nicotinamide-adenine-dinucleotide and reduced nicotinamide-adenine-dinucleotide-phosphate and at least one SH-group containing a compound as stabilizing agent and thereafter lyophilizing the solution thereby formed, wherein said SH-group containing compound is a member selected from the group consisting of cysteine, cysteine carbamide, acetyl-cysteine, glutathione, homocysteine thiolacetone, N-acetylhomocysteine, thiolactone, and thioglycollate.

14. Process for carrying out a biological or chemical test procedure requiring reduced nicotinamide-adenine-dinucleotide or reduced nicotinamide-adenine-dinucleotide phosphate as a coenzyme which comprises dissolving the composition of claim 1 in water, introducing into the solution thereby formed a liquid sample containing a material to be investigated and examining the resultant solution for evidence of the presence and/or amount of said material.
